UNITED STATES PATENT OFFICE

LOUIS B. HASBROUCK, OF ELMIRA, AND JOHN P. GAREY, OF ELMIRA HEIGHTS, NEW YORK, ASSIGNORS TO ECLIPSE TEXTILE DEVICES, INC., OF ELMIRA, NEW YORK, A CORPORATION OF NEW YORK

DYEING APPARATUS

Application filed September 3, 1930. Serial No. 479,492.

This invention relates to apparatus for impregnating fibrous material with dye or other liquids by injection.

Injection dyeing apparatus and an injection needle containing an open groove are the invention of Henry E. VanNess, described in his U. S. Patents Nos. 1,577,884, 1,734,455, 1,584,335 and 1,606,196. The VanNess injection dyeing apparatus has been extensively used for carrying out the VanNess method of yarn spotting described in his Patent No. 1,456,344.

The principal object of the present invention is to provide means for utilizing the VanNess injection apparatus for solid dyeing of a package of yarn. The invention provides an automatic machine for this purpose which has advantages over the ordinary apparatus for solid dyeing in economizing the amount of dye used, avoiding a straining of the dye, and in facilitating perfectly even dyeing of the whole mass.

While the primary object of our invention is to produce a machine for solid dyeing, several features of the invention may advantageously be used in yarn spotting machines.

In our invention, we have departed from the arrangement shown in the VanNess dyeing machine patents, Nos. 1,577,884, 1,584,335 and 1,606,196, by providing for thrusting the injection needles into the mass of yarn by a movement of the needles instead of a movement of the mass. By this change, we are enabled to operate simultaneously upon different surfaces of the mass and in particular to thrust injection needles into opposite surfaces, thus dyeing a portion of the mass twice as deep as that which can be dyed when the needles are stationary. This enables us to dye a wound mass by thrusting the injection needles into its opposite ends, which tends to produce more rapid and even dyeing than can be obtained by radially-positioned needles.

Another feature of our invention consists in completely confining the mass of yarn during the injection. This enables us to apply an even pressure to the whole mass at the time of the injection, which tends to promote the evenness of the dyeing.

Our invention may best be understood from a detailed description of a practical dyeing machine involving all the above-mentioned features of our invention, as well as other features hereinafter referred to. Such a machine is illustrated in the accompanying drawings, in which:

Fig. 1 is a plan view of the machine;

Fig. 2 is an end elevation of the machine;

Fig. 3 is a front elevation of the machine;

Fig. 4 is an enlarged section taken on the line 4—4 of Fig. 3;

Fig. 5 is an enlarged vertical section showing the injectors in operative relation with a mass of yarn supported in the workholder;

Fig. 6 is an enlarged plan view of the guideways;

Fig. 7 is an enlarged section showing the mechanism for imparting rotary movement to the injectors and the passageways leading from the rod to the injectors;

Fig. 8 is an enlarged end elevation of the mechanism for imparting rotary movement to the injectors and showing the relative positions of the outlet openings.

The yarn dyeing machine illustrated in the drawings has a frame comprising a T-shaped table top or plate B supported on end frames B1, B2 at its front corners and a leg B3 at its rear corner. On the plate are mounted a fixed workholder W, and two sets of injectors J, having injecting needles J2, held in carriers J3 which are movable to thrust their needles J2 into a mass of yarn C in the holder W through different surfaces thereof. The injector carriers J3 have surfaces which contact evenly with the surface of the yarn mass C into which the injector needles J2 are inserted, and the carriers J3 are so formed that they cooperate with the workholder W completely to enclose the mass of yarn C when their needles J2 have been thrust into the mass.

In the form illustrated, the workholder W consists of a horizontal open-ended cylindrical casing having a fixed lower part W2 mounted on a pedestal W3 secured to the plate B and a hinged upper part or cover W4 which may be tipped back to permit the insertion of a mass of yarn C and locked in

closed position by a spring latch W6 after the mass has been inserted. The injector carriers J3 have the form of discs fixed on the ends of rods J4 slidably mounted in bearings J6 secured to the plate B at opposite ends of the workholder W with their axes aligned with that of the workholder, so that the carrier discs J3 may be moved axially towards and away from the open ends of the workholder W. The diameter of the carrier discs J3 is such that they just fit within the workholder W, so that they may cooperate with the workholder completely to enclose a cylindrical package of yarn C therein, as clearly shown in Fig. 5. The injectors J project from flat surfaces of the carrier discs J3 which correspond to the flat ends of a cylindrical yarn package C in the holder W, so that they come into complete contact with the ends of the package C when they are moved into the position shown in Fig. 5. The injectors illustrated consist of nozzles J7 and needles J2 having open grooves and are thus substantially like the injectors shown in Van Ness Patent No. 1,577,884. It is, however, not essential to use this specific form of injector.

The machine provides for automatic operation of the injectors J to effect solid dyeing of a cylindrical yarn package C in the holder W. Automatic power-driven means are provided for moving the injector carriers J3 simultaneously towards and away from the yarn C to thrust their needles J2 into the yarn C and withdraw them therefrom. With the insertion and withdrawal means are combined means for causing an angular movement of the injector carriers J3 after each withdrawal, so as to insert the needles J2 successively into adjacent portions of the mass. With the insertion and withdrawal means is combined also an automatic control for a power-driven pump P which is operated to force dye into the yarn C through the injectors J after each insertion of the injectors.

The means for causing the inward and outward movements of the injectors J comprises a power-driven pulley J8 on a longitudinal shaft J9 mounted in bearings J10 on the top of the plate B, and connected by bevel gears J11 with a short transverse shaft J12 which, through spur gears J14, J15, drives a counter-shaft J17, on which are fixed oppositely positioned eccentrics J18, whose straps J19 are connected by rods J21 with levers J22, whose lower ends are pivoted to the end frames at J24. The upper ends of these levers carry yokes J25 connected to cross-heads J26 containing rotatable studs J27 which connect with the outer ends of the rods J4 upon whose inner ends the injector carriers J3 are mounted so that oscillation of the levers J22 causes reciprocation of the rods J4 and the injector carriers J3 on them. Manual movement of the injectors J is provided for by introducing a clutch J28 between the driving pulley

J8 and the shaft J9, and providing a hand crank J29 on the countershaft J17.

To permit a dwell of the injector carriers J3 at the inner ends of their strokes, the studs J27 are connected to the rods J4 through springs J31 which serve to permit a slight inward movement of the upper ends of the levers J22 after the inward movement of the rods J4 has been stopped by contact of the injector carriers with the ends of the package of yarn C in the holder W. This inward movement of the power-driven levers J22 during the dwell serves to compress the springs J31 and thus to cause them to urge the rods J4 and injector carriers J3 inward to compress the yarn package C confined by them and the workholder W.

The means for causing an angular movement of each injector carrier J3, after the withdrawal of its needles J2 from the yarn mass C, includes a ratchet J34 secured to each injector carrier J3, and a pawl J35 carried on a frame J36 rotatably mounted on the injector carrier J3 and having a detent J37 extending into a guide slot J38 which is shaped to cause a slight rotational movement of the frame J36 and pawl J35 during the latter part of the outward stroke of the injector carrier J3 after the needles J2 have been withdrawn from the yarn C.

The injector needles J2 in the two opposite carriers J3 are placed out of line with each other, in order that there may be no chance of bringing the points of any two needles J2 into contact with each other, in case the needles are inserted slightly more than half way into the mass C. To preserve this spaced relation between the needles J2 of the two carriers J3, the guide slots J38 are so arranged that the simultaneous angular movements of the carriers J3 which occur on each withdrawal are in the same direction, so that the relative position of the needles J2 of the two carriers J3 is not changed by such angular movements.

A power-driven pump P is utilized to force limited quantities of dye through the injectors J of the two carriers J3 under equal pressures on each insertion of the injectors. The pump P is driven by power applied to a constantly rotated pulley P2 at the rear of the machine. This pulley P2 is connected through a punch-press clutch P3 to a short transverse crankshaft P4 under the plate B at the rear of the machine. The crank P5 on this shaft is connected to the piston P6 of the pump P. The punch-press clutch P3, and consequently the operation of the pump P, is controlled by a cam P7 on the transverse countershaft J17, which engages a rod P8 just as the needles J2 have entered the mass C to cause one complete rotation of the crankshaft P4 in which the pressure stroke of the pump P occurs during the dwell of the injectors J permitted by the resilient connec-

tion between the rod J4 and the levers J22, and while the springs J31 are applying pressure to the confined yarn mass C. The liquid discharged by the pump P is conducted through pipes P9 which enter the bearings J6 of the rods J4, and communicate with the injectors J through bores J40 in the injector carriers J3 and bores J41 in the rods J4. Such communication is provided by radial holes J42 in the rods which are positioned to communicate with the ends of the pipes P9 when the rods J4 have been moved inwardly and in any angular position of the rods.

15. What is claimed is:

1. In apparatus of the class described, the combination with a holder for an absorbent mass, of a plurality of injectors mounted for movement towards and away from said holder in different directions so that they may be brought into engagement with different surfaces of the mass therein.

2. In apparatus of the class described, the combination of a fixed holder for an absorbent mass, a pair of movable injectors, and means for simultaneously thrusting said injectors into said mass through opposite surfaces thereof.

3. In apparatus of the class described, the combination of a fixed holder for a wound mass of yarn, a pair of injectors mounted for movement parallel to the axis of the mass in the holder, and means for simultaneously moving said injectors toward the holder to bring them into contact with opposite ends of the wound mass.

4. In apparatus of the class described, the combination of a fixed holder for an absorbent mass, a plurality of injectors mounted for movement towards and away from said holder in different directions, means for moving the injectors towards the holder to bring them into contact with opposite surfaces of the mass, and means actuated by the injector movement for forcing liquid through the injectors into the mass when the injectors are in contact with the mass.

5. In apparatus of the class described, the combination with a holder for an absorbent mass, of an injector, a rod slidably mounted for movement towards and away from said holder, and a carrier for the injector mounted on one end of said rod.

6. In apparatus of the class described, the combination with a holder for an absorbent mass, of a rod mounted for sliding movement towards and away from said holder and containing an axial passage and a lateral port, an injector mounted on one end of said rod in communication with the axial passage therein, and a conduit positioned to communicate with said port when the injector is positioned close to a mass on the holder.

7. In apparatus of the class described, the combination of a holder for an absorbent

mass, an injector, a rod carrying said injector on one end, means for reciprocating said rod longitudinally to bring the injector into and out of contact with the surface of the mass in the holder, and means permitting a well at the end of the inward stroke of said rod.

8. In apparatus of the class described, the combination of a holder for an absorbent mass, an injector, a rod carrying said injector on one end, means for reciprocating said rod longitudinally to bring the injector into and out of contact with the surface of the mass in the holder, means permitting a dwell at the end of the inward stroke of said rod, and means actuated by said reciprocating means to inject dye into the mass through the injector during said dwell.

9. In a yarn dyeing machine, the combination of a holder for a wound mass of yarn, a dye injector including a needle parallel to the axis of a wound mass on the holder, and means for causing relative movement of the holder and the injector to thrust the needle into the mass in a direction parallel to the axis of the mass.

10. In apparatus of the class described, the combination of a holder partially enclosing an absorbent mass, dye injecting means, means carrying said injecting means and formed to cooperate with said holder completely to enclose the absorbent mass, means for causing relative movement between said carrying means and the holder to enclose and expose said mass, and means for forcing dye into the mass through the injecting means when the mass is enclosed.

11. In apparatus of the class described, a holder for a wound mass formed to enclose the circumferential surface thereof, reciprocatory members movable into and out of contact with the ends of the mass in the holder, and means for injecting liquid into the mass when it is enclosed by said holder and said reciprocatory members.

12. In apparatus of the class described, a hollow cylinder adapted to enclose the circumferential surface of a cylindrical wound mass of yarn, a pair of discs adapted to fit within the ends of said cylinder to enclose the ends of a mass of yarn therein, means for simultaneously reciprocating said discs to bring them into and out of contact with the end of the mass, and means for injecting dye into the mass through the discs when they are in contact with the ends of the mass.

13. In apparatus of the class described, means for injecting liquid into an absorbent mass having a flat surface comprising a carrier having a flat surface, a plurality of injectors projecting from the flat surface of said carrier, and means for pressing the flat surface of the carrier against the flat surface of the mass and injecting liquid into the mass through the injectors.

14. In apparatus of the class described, a holder for a wound mass formed to leave a portion of the surface of the mass exposed, an injector-carrier having a surface formed to fit against an exposed surface of the mass in the holder, a plurality of injectors projecting through said surface of the carrier, means for causing relative movement between the holder and the carrier to press said surface of the carrier against an exposed surface of the mass, and means for injecting liquid into the mass through said injectors while said surface is pressed against the mass. 70
15. In apparatus of the class described, a plurality of relatively movable confining members formed to cooperate in completely confining and evenly compressing an absorbent mass, one of said members containing holes therethrough, and means for injecting liquid into the mass through said holes when the mass is compressed by said members. 80
16. In apparatus of the class described, the combination of a circumferential holder for a wound mass of yarn, plungers adapted to enter the ends of the holder to compress the mass of yarn therein, said plungers containing holes therethrough, and means for injecting liquid into the mass through said plungers when compressed by the holder and plungers. 85
17. In apparatus of the class described, the combination of a hollow cylindrical holder having open ends, reciprocatory plungers adapted to enter the ends of the holder to compress an absorbent mass therein, and means for injecting dye into the mass while compressed by said plungers. 90
18. In apparatus of the class described, the combination with a holder for an absorbent mass, of an injector, a carrier for said injector mounted for movement towards and away from the mass in the holder, a reciprocatory actuator for said carrier, and a resilient connection between said actuator and the carrier permitting a dwell at the end of the inward stroke of the carrier when said carrier is pressed against said mass. 95
19. In apparatus of the class described, the combination with a holder for an absorbent mass, of an injector, a carrier for said injector mounted for movement towards and away from the mass in the holder, a reciprocatory actuator for said carrier, a resilient connection between said actuator and the carrier permitting a dwell at the end of the inward stroke of the carrier when said carrier is pressed against said mass, and means actuated by said reciprocatory means to inject dye into the mass through the injector during said dwell. 100
20. In apparatus of the class described, the combination with a fixed holder for an absorbent mass, of an injector directed towards said mass and mounted for movement to- 105
- wards and away from the mass and for lateral movement, means for reciprocating said injector to move it into contact with and away from the mass in the holder, and automatic means for causing a lateral movement of the injector after each inward movement thereof. 110
21. In apparatus of the class described, the combination with a holder for an absorbent mass, of an injector having a needle directed toward the mass in the holder, means for reciprocating said injector in a direction parallel to its needle to thrust the needle into the mass and to withdraw it therefrom, and automatic means for causing a lateral movement of the injector on each outward movement thereof after the needle has been withdrawn from the mass. 115
22. In apparatus of the class described, the combination with a fixed holder for an absorbent mass, of two banks of injector needles directed towards opposite surfaces of a mass in the holder, the needles of one bank being out of alignment with those of the other bank, means for simultaneously reciprocating said banks of needles to thrust them into the mass and withdraw them therefrom, means operative after each withdrawal to cause equal lateral movements of the two banks of needles in the same direction to retain the needles of each bank out of alignment with those of the other bank. 120
23. In apparatus of the class described, the combination of a holder for an absorbent mass, injecting means for introducing limited quantities of liquid into a mass on the holder, automatic means for causing successive injections through said injecting means, and automatic means for so changing the relative position of the injecting means and the holder after each injection as to cause successive injections to color the entire mass. 125
- In testimony whereof we have hereunto set our hands.
- LOUIS B. HASBROUCK. 110
JOHN P. GAREY.
